By Attorney

UNITED STATES PATENT OFFICE

100,100

DESIGN FOR A DESK THERMOMETER OR SIMILAR ARTICLE

Harry Germanow, Rochester, N. Y., assignor to
Germanow-Simon Machine Company, Rochester, N. Y., a firm composed of Harry Germanow
and Julius Simon

Application February 26, 1936, Serial No. 61,365

Term of patent 14 years

To all whom it may concern:

Be it known that I, Harry Germanow, a citizen of the United States residing at Rochester, in the county of Monroe and State of New York, have invented a new, original, and ornamental Design for a Desk Thermometer or Similar Article, of which the following is a specification, reference being had to the accompanying drawing, forming part thereof, and in which:

Figure 1 is a perspective view of a desk thermometer or similar article showing the new design, and

Figure 2 is a side elevation of the same.

The dominating features of the present design consist in a base portion, and a pedestal portion of smaller diameter rising from and within the base portion and of substantially greater height at its rear as compared to its front, to thus present a dial supporting surface inclined to the horizontal in a forward, downward direction, as shown.

I claim:

The ornamental design for a desk thermometer or similar article, substantially as shown and described.

HARRY GERMANOW.
